US0D1058001S

(12) **United States Design Patent** (10) **Patent No.:** **US D1,058,001 S**
(45) **Date of Patent:** **** Jan. 14, 2025**

(54) **PANEL**

(71) Applicants: **Dolby Laboratories Licensing Corporation**, San Francisco, CA (US); **Dolby International AB**, Dublin (IE)

(72) Inventors: **Paul Arnulf Frick**, San Jacinto, CA (US); **Matthew William Clare**, Mill Valley, CA (US); **Xiaoxi Zhang**, Shanghai (CN); **Rui Bao**, Beijing (CN); **Yifan Wu**, Beijing (CN); **Giovanna Buccharone**, Rome (IT); **Brent Warren Behringer**, Hemet, CA (US); **Pascal Sijen**, La Quinta, CA (US); **Douglas J. Gorny**, Pacifica, CA (US); **Gilbert K. Lee**, Fremont, CA (US); **Christopher R. Kukshtel**, Sonoma, CA (US); **Peter Michaelian**, San Francisco, CA (US); **Su Jiao**, Shanghai (CN)

(73) Assignees: **Dolby Laboratories Licensing Corporation**, San Francisco, CA (US); **Dolby International AB**, Dublin (IE)

(**) Term: **15 Years**

(21) Appl. No.: **29/797,690**

(22) Filed: **Jul. 1, 2021**

(51) LOC (15) Cl. **25-01**

CLAIM

The ornamental design for a panel as shown and described.

DESCRIPTION

FIG. 1 is a front perspective view of a panel showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
